(57) **CLAIM**

The ornamental design for a blank for forming a container, as shown and described.

DESCRIPTION

FIG. 1 is a top plan view of the blank for forming a container showing the new design, the bottom view is a mirror image of the top view;

FIG. 2 is a front view thereof, the back view is a mirror image of the front view;

FIG. 3 is a right side view thereof, the left side view is a mirror image of the right side view; and,

FIG. 4 is a top perspective view thereof.

The broken lines in the figures are illustrative of features that form no part of the claimed design.
